5 Claims. (Cl. 209—110)

This invention relates to a machine for automatically sorting punched cards and has numerous advantages over similar devices used at present.

Following is the description of a method and means for practicing the invention, reference being had to the accompanying drawings in which:

Fig. 1 is a substantially transverse sectional view of the improved sorter;

Fig. 2 is a plan view of the grid plates controlling the movements of the supporting levers;

Fig. 3 shows in perspective the action of the grid plates;

Fig. 4 represents diagrammatically the details of the supporting levers and their movements;

Fig. 5 is a plan view of the upper part of the supporting lever motions;

Fig. 6 shows the detail of the fork controlling the blades guiding the cards;

Fig. 7 is a view of the blades seen from underneath;

Fig. 8 shows in perspective the blades as they are raised by the fork;

Fig. 9 is a substantially longitudinal sectional view of a modified form of the invention illustrated in Figures 1 and 4;

Fig. 10 is a transverse diagrammatic elevational detail of the selecting mechanism looking from the left in Fig. 9;

Fig. 11 is a plan view of the blades used in Fig. 9;

Fig. 12 shows a cross section of the blades along the line 200 in Figure 11;

Fig. 13 shows the same cross section, but along the line 201 in Figure 11;

Fig. 14 shows the same cross section, but along the line 202 in Figure 11;

Fig. 15 shows the same cross section, along the line 203 in Figure 11;

Fig. 16 is a perspective view of the carriage of the card holder;

Fig. 17 shows the detail of the tilter of the carriage card holder;

Fig. 18 shows the mode of operation of this tilter in connection with the rib of the frame;

Fig. 19 shows the group formed by the tilter and the lever that drives it;

Fig. 20 shows the spring which detains the cards while they are explored;

Fig. 21 shows the electrical reading or exploring of the cards by means of a moving brush;

Fig. 22 is a circuit diagram of the relays and electro-magnets of the preceding device;

Fig. 23 shows the mechanical and electrical drive for the ratchet motions;

Fig. 24 shows the section of single selectors used when sorting in several columns simultaneously;

Fig. 25 shows the detail of an exploring needle used as commutator;

Fig. 26 shows the action of single selectors 5 when the cards are read electrically;

Fig. 27 is a device to compare relative values of two figures;

Fig. 28 is a diagram of the device used to insert the separation cards; 10

Fig. 29 shows the detail of the automatic hooking of the carriage card holder;

Fig. 30 is a circuit diagram for controlling the replacement of cards; and

Fig. 31 is the special needle used to find the 15 separation cards.

The sorting machine is constructed as follows:

A card feeder 1 (Fig. 1) moves the cards one at a time in the usual manner under a reading comb 2, consisting of four needles 3, 4, 5 and 6, assembled on springs in a frame, laterally movable in

order that it may be led above the card column to be sorted. Furthermore, in line with the "lines" of the holes of the card (underneath the punch holes) four plates 7, 8, 9, 10 (Figs. 1 and 2) 20

rest on the rods 11, 12, 13 and 14. These plates are held at their ends by small levers 17 (Fig. 3)

mounted on pivots 19 screwed to the frame of the sorter; they are held on a fixed horizontal plane by the rods 11, etc., which rest on the bar 18 by 30

means of springs such as 15 and a ring 16. Finally, the lower ends of the rods 11, 12, 13, 14

are, when not working, placed a fraction of a mm. above the four levers 20, 21, 22 and 23. 35

Furthermore (Fig. 4), four parts of a parallel-

opiped 24, 25, 26, 27, and a fifth one 28, which

is part of the frame, can, with the exception of 40

28, which is fixed, slide one over the other. These

parts are all pulled in the direction of the progress 45

of the cards by the pairs of springs 29, 30, 31,

32 (Figs. 4 and 5). The parts are normally held 50

at the end of their stroke, corresponding to the taut position of the springs by the stops 37,

38, 39, 40, and the catches 33, 34, 35, 36. The 55

latter are integral parts of the levers 20, 21, 22,

23, respectively, the levers being pivoted at 41,

42, 43, 44 on the parts 25, 26, 27, 28, and actuated by the springs 45, 46, 47, 48, when the catches 55

33, etc., free the stops 37, etc. The parts 24,

25, 26, 27 are moved by the springs 29, 30, 31, 32

until they meet the stops 49, 50, 51, 52 of the part immediately below.

The movement of the part 26 relatively to the

part 27, is twice as long as that of the part 27 55

relatively to the frame, and the relative movement of the part 24 is double that of part 25.

It will be seen that the part 24 will move, with respect to the frame, a distance equal to the sum of relative movements of the parts 24, 25, 26 and 27, and with respect to 25, 26, 27, 28. Furthermore, all numbers below 16 can be broken up into a series or sum of terms equal to 1, 2, 4, 8. To each number 1, 2, . . . 16, a system of movements of the parts 24 . . . 27 corresponds, and vice versa.

The part 24 has an extension 53 (Figs. 1, 4, 5, 6) in which a hole is bored (square for example) 54 and through which passes a rod of similar shape 55 having a shoulder 56 and held towards the lower end by a spring 57, resting on the screw head 58. This rod 55 ends at its upper part in a beveled fork 59.

The screw head 58 is placed a fraction of millimeter above a plate 60 (Fig. 1). By the means of a bell crank 61, 62, driven by the cam 63 fixed on the main shaft of the sorter, plate 60 will be raised at the desired moment.

Then a cam 69 fixed on the main shaft operates, by means of a rod 90 and a lever 94, which at the desired moment returns the part 53 and then the parts 24, 25, 26, 27 into a position of rest against the stops 25', 26', 27' held, respectively, by 25, 26, 27.

Furthermore, sixteen thin steel blades 65, 66 . . . 67, 68, which open into card compartments move above the fork 59, as shown in the Figs. 4 and 7, the latter showing these blades as seen from below. Their shape is shown in Fig. 7; they narrow down from a few centimeters at their extremity and end all in the vertical plane 69. However, the distances of the widening points at that extremity increase proportionally to the number of the blade. Furthermore, the distance between the widenings of two consecutive blades is equal to the movement d of the part 27. Finally, in its position of rest, the fork 59 is placed in the vertical plane 70, which is located at a distance

$$\frac{d}{2}$$

from the vertical plane in which lies the widening of the blade 68.

From then on, the operation is as follows: when the card comes below the needles 3, 4, 5, 6, the frame and the comb 2 driven by the eccentric 71 and the connecting rod 72, which are lowered, the needles which meet a hole in the card, go through said hole, and after being locked, they bear on the grid plates 7, 8, 9, 10. These plates actuate in turn some of the rods 11, 12, 13, 14, which, by means of the levers 20, 21, 22, 23, and the catches 33, 34, 35, 36, free one or more parts 24, 25, 26, 27. The rod 55 is moved in the same direction as the cards, the length of motion depending on the holes of the card that is being read. At this moment the cam 63 raises the plate 60 by means of the bell-crank 61; this plate drives up the rod 55, the beveled fork 59 of which raises one of the blades such as 67 (Fig. 8) as well as all those that are above said blade 67.

Meanwhile, the frame 2 frees the card which has been moved, as will be explained below, between the two series of blades held apart by the fork 59. Then, the card fed in the usual manner by rolls or pushers will glide between the blades 65 . . . 68, until it falls into the desired bin. However, the cam 69 has actuated the lever 94, 75 and the parts 24, 25, 26, 27 have returned to their

position of rest: a new card can then be read, and so on.

The above described device may be modified so as to facilitate or permit an increase in the speed of operation. Accordingly, the partial assembly, according to Fig. 4, and the shape of the blades (Figs. 7 and 8) are changed as follows: the parts such as 24, 25, 26, 27, are divided into two identical series; one remains unaltered, whereas the other is placed perpendicularly to the first. In Figs. 9 and 10, the two first parts of these series are shown by 191 and 192 and the other two by 193 and 194. The part 191 is extended and four rods 195, 196, 197, 198, pass through it, doing the work of the rod 55 (Fig. 4). Those rods are shown one behind the other (Fig. 9) and seen in profile (Fig. 10); they slide vertically in 191 and are brought back individually downwards, by draw-springs such as 204. The part 193 is also extended and is fitted with a plate 199 the dimensions of which according to the plane of Fig. 9, are equal to the width of the rods 195, plus the total possible displacement of the parts 191 and 192. The plate 199 is placed above a plate 60', which corresponds to plate 60 in Fig. 1 but is widened so as always to meet the plate 199 whatever the positions of the parts 193 and 194 may be. The parts 20, 21, 22, 23 of these figures are actuated by the rods 11, 12, 13, 14 (Fig. 1) in the manner indicated above or in any suitable manner.

On the other hand the blades 66', 67, and 68' have been modified as will be shown in Figs. 11 to 15. They are not narrowed down as shown in Figs. 7 and 8, but holes of variable dimensions are bored through them; the upper blade is not bored at all, the blade that holds it, is bored along the axis 200 and of a single length; the two following blades are bored along the same axis and of double, triple length, respectively, and all the other blades have all a hole bored along the axis 200 and of a quadruple length, as is indicated in Fig. 12, which shows a cross section along the axis 200 of Fig. 11. In addition to these holes, the second series of four blades has holes bored along the axis 201 (Fig. 13), and is similarly disposed. This applies as well to the third series (Fig. 14) and the fourth series (Fig. 15). Then the rods 195 . . . 198 are, respectively, in the plane of 200 . . . 203 and the movements of 191 are parallel with these planes.

The operation is as follows: the displacement of the parts 193 and 194 along the plate 199, determines which one of rods 195, 196, 197, 198 will be raised and so chooses a series of four blades, while the displacement of the parts 191 and 192 determines in this series which blade will be raised.

The advantages of these devices over prior structures are that the maximum displacement of the rods 191 and 193 is limited to three units instead of 15; and that the speed of the entire device can thus be materially increased.

It is to be noted that the drive of the levers 20 . . . 23, whether it applies to the device of Fig. 4 or to the modification shown in Figs. 9 and 10, can operate differently than that shown in Fig. 1, and particularly, this drive can be effected by using cards punched with only one hole per column. In this case as many exploring needles or rods are disposed per column, as there are possible positions to punch in that same column, and this needle or rods drive, by means of suitable devices, one or many rods 11 . . . 14, depending on the position of the perforation or punch.

The displacement of the card can be effected, until the final feed, very simply by means of a carriage card holder which is constructed as follows:

5 The carriage card holder consists of a plate 73 (Fig. 16) shaped like a grid without cross bars, the longitudinal bands being separated by twice the distance between two consecutive columns of the card. This plate has slides 74, which hold it 10 in the frame of the sorter; it has extensions 75, retaining the cards in the stack when the carriage is in a forward position; it has a lever 77 and the tilt 78. This tilt 78 is bent back at its lower end in 79 (Fig. 17). During the travel 15 of the carriage 73, the dog 79 rests on the rib 80 of the frame (Fig. 18). The length of this rib is less than the length of the travel of the carriage 73, so that, at each end of the travel 20 or the stroke, the dog 79 is freed of the rib 80. Upon the start of the carriage 73, the dog 79 25 bumps against the extreme face of the rib 80, and whatever the direction of the carriage feed, the pivot 81 of the tilt 78 is always ahead of the dog 79. The end 82 of the lever 77 is slightly longer than the surface of the carriage 73 (Fig. 19), when said lever obeys the action of the 30 spring 83, which tends to make it turn around the screw 85, until it meets the stop 84 which is part of the carriage. During the backward 35 movement of the carriage, the tilt under the action of the rib 80, tilts the lever 77, the head 82 of which disappears.

The feed spring 76 consists of a very flexible blade fixed at its center on the carriage 73 in order to overcome a possible adhesion of the 35 cards. It has also two feeding embossings.

Fixed to the frame (between the needles 3, 4, 5, 6 and the grid plates 1, 8, 9, 10) there is another grid 86 (two bars of which are shown as 40 an example, Fig. 16) identical with the one on the card holder but fixed. The distance between the bars is equal to double the separation between two columns of the card.

This carriage feeds a card in a forward movement until it rests on the grid 86; during this movement, the card is pushed under two springs 87 (Fig. 20) (one on each side of the device) fixed at 88. Due to the provision of stop 95, the 45 springs retain the card to remain on the grid 86 when the card holder backs up. During the period of rearward movement of the carriage, the tilt 78, after bumping against the rib 80, operates the lever 77, in order that the nose 82 disappears and pass under the card that is being read on the grid 86, without hooking it at the end of its stroke. At the completion of the rearward movement of the carriage the tilt 78 is freed and the nose 82 comes up. When the carriage resumes its forward movement, a new card is fed 50 by means of a spring 76 and the preceding card will be pushed by the nose 82 until it is taken between two rolls or fed through fingers fixed on an endless chain.

The purely mechanical operation of this device necessitates that the card stop. This inconvenience can be avoided if the reading is done electrically. To that end, the card taken by the rolls 55 96 when it leaves the card holder, is passed under a reading brush 97 (Fig. 21). In order to allow the card to pass more rapidly while allowing sufficient time for the holes under the brush, the latter is held by a bar 98 which moves on slides 99, and which is moved along the slides by a cam 100, 60 fixed on the shaft of the device by means of a 65

lever 101. If the cam 100 has a suitable profile, the relative speed of the card and the brush can be sufficiently decreased during the reading so that the relays will have sufficient time to function.

5 The main shaft carries a distributor 102 (Fig. 22) and its brush 103 engages the contacts 104, 105, 106, 107, while the four lines of holes of the card pass under the brush 97. The current flows from the source 108 through the brush 103, terminals 104 to 107 to one of two windings of the relays 109, 110, 111, 112; then it returns to the source through the brush 97 and the holes of the card. The relays 109 to 112 close through their secondary winding, a holding circuit in 113, 114, 15 115, 116, 117, 118, and in 114, 123, 124, 125, 126, the energizing circuit of the electro-magnets 119, 120, 121, 122; these last electro-magnets actuate, respectively, the levers 20 . . . 23 and thus replace the rods 11 . . . 14. The balance of the device is identical with that of Figs. 1 and 4 or 9. An interrupter 127 connected in the return wire common to all the "electro-magnets" opens for an instant at the opportune moment, under the control of a finger 128 fixed on the main shaft. 20

An interrupter, which can be short circuited, is provided at 147 and 148.

The electro-magnets 119, 120, 121, 122 are assembled as it is shown for one of them in Fig. 23; 30 its armature 129 rests on the lever 20 (Figs. 1, 4 and 9); furthermore, a cam 133, fixed on the main shaft, makes the armature rest upon the core, by means of rods 130 and 132, and of the bell crank 131; this mechanical contact lasts only for a very short time and takes place as soon as the relays 109, 110, 111, 112, have functioned and during the action of the cam 89 on the lever 94. The energized electro-magnets will continue to free the parts 24, 25, 26, 27, after the setting back of the lever 94, while the others will have let go 40 their armature before this set back.

As soon as the parts 24, 25, 26, 27 have moved, the finger 128 opens the circuit of the electro-magnets and relays, and all the parts return to the original position.

45 This kind of device, whether the reading be mechanical or electrical, lends itself to adaptation in a speed counter; it will be necessary to equip the part 59 with a knife 134 (Fig. 6) which, when the plate is raised, will press on a bell crank 135, 50 acting by means of rods or wires on a speed counter 136; a similar mounting will be provided for each one of the possible positions of the part 59. An obvious variation must be provided in 55 the case of the device shown in Figs. 9 to 15.

To operate the sorting means on several columns at a time, i. e., to sort only cards in which a certain number of columns has been predetermined, the other cards going into the "reject" 60 compartment XVI, the following device is used:

It has been seen above that the parts 24, 25, 26, 27, were brought back to their original position by means of the cam 89, the rod 90 and the lever 94. After passing the shoulder embossing 65 of the cam 89, the lever 94 returns to its original position under the action of a spring. If, then, rod 90 is blocked, the lever 94 stays in its working position and the parts 24 . . . 27, being unable to move, the part 59 raises no blade; all the 70 cards travel then to the end compartment XVI. The same result will be obtained in blocking the rod 62, because the plate 60 will not rise; one can choose the modification best suited for the practical application of the device.

The rod 90 (Fig. 24) has a slot 137, in which a bolt 139 engages, held by the armature of the electro-magnet 138. It will be clear that if that electro-magnet is not energized when the cam 89 5 frees the rod 90, the latter will remain blocked by the bolt 139 which will be raised under the action of the spring 140 at the moment when the slot 137 above it is passed. When the magnet is energized the rod 90 will respond to a spring and 10 will free the parts 24, 25, 26, 27.

In the case of mechanical reading, the card holder in the shape of a grid allows the card to be explored by needles or feelers going through the holes of the cards. The individual selectors may be 15 freed by means of relays. For this purpose, each needle 3 is equipped with a sheath consisting of a middle part 141 of conductive material disposed between two insulated parts 142 and 143 (see Fig. 25). Three small springs 144, 145, 146, act 20 as the contacts of the relays. In the lower position of the needle, the springs 145 and 146 are short circuited by the sheath 141, thereby closing a circuit through a relay which frees the selector corresponding to the lowered needle. In the 25 higher position, the two springs 144 and 145 are short circuited and close a circuit through the electro-magnet 138 (Fig. 24), in order to free the push back arm 90.

In case the reading is carried out by means of 30 brushes and electro-magnets (assembly of Fig. 22), an arrangement can be used, as shown in Fig. 26, in which the relays 109' to 112' of that figure take the place of the relays 109 to 112 of Fig. 22; their return wire being connected to 35 the brush 97' of the column to be fixed in advance; as to the secondary circuit formed by studs of the contacts, it will suffice to insert it in 147, 148, in the return wire to the electro-magnets 119 to 122. If several columns are prepared, the relays 40 must all be mounted as described above and all the secondary circuits will be placed in series together.

In case the reading is done mechanically, the device compares the relative values of two numbers preferably modified as follows (Fig. 27):

For each column, a series of four needles such as 180, 181, 182, 183 are provided, each forming a commutator due to an insulated sheath conductor placed between two insulated sheaths, and two 50 identical series of four resistances 184, 185, 186, 187, and 184', 185', 186', 187', the values of which are as follows:

$$R187 = 2 \times 186 = 4 \times R185 = 8 \times R184 = 8r$$

$$R187' = 2 \times R186' = 4 \times R185' = 8 \times R184' = 8r$$

($\times$ means: multiplied by)

These resistances are connected to the springs coming into contact with the needles 180, 181, 182, 183, as the figure indicates, that is:

60 In the lower position of the needles (position assumed in Fig. 27):

The needle 180 short-circuits the resistance 187'
181 short-circuits the resistance 186'
182 short-circuits the resistance 185'
183 short-circuits the resistance 184'

In the high position of the needles:

The needle 180 short-circuits the resistance 187'
181 short-circuits the resistance 186'
182 short-circuits the resistance 185'
183 short-circuits the resistance 184'

70 The free end of the resistance 184 is connected at 188 to a contact of the source of current, and 75 the free end of the resistance 184' at 189 to the

other contact, while the free ends of the resistances 187 and 187' are united in a point 190, which point will be connected to a terminal of a polarized electro-magnet.

Disregarding the disturbance created by the 5 introduction in the circuit of the winding of that electro-magnet, it will be evident that whatever the position of the needles, the total resistance inserted between 188 and 189 is constant, and is equal to 15r. Under these conditions, if 15V 10 designates the tension between the terminal 188 and 189, and V1 is the tension between 188 and 190, V2 is the tension between 190 and 189, the following is obtained when the four needles are in the lower position:

$V_1 = 15V$	$V_2 = 0$
Needle 183 alone raised, $V_1 = 14V$	$V_2 = V$
182 alone raised, $V_1 = 13V$	$V_2 = 2V$
181 alone raised, $V_1 = 11V$	$V_2 = 4V$
The needle 180 rises alone $V_1 = 7V$	$V_2 = 8V$

Then this device constitutes a potentiometer which gives for each combination of holes, passing under the needle, a tension which increases in arithmetical progression between the points 189 25 and 190 for example, and decreases equally between 190 and 188.

In case of electrical reading, the same device can be used, but it would be necessary to replace the commutators carried by the needles 180, 181, 30 182, 183, by relays. However, these relays would have the advantage over those of the first mentioned device, that they are identical and act only as bipolar interrupters; their armature would be lighter.

The device disclosed in said French Patent 619,625 and which permits simultaneous sorting on several columns, has the great advantage to give in one passage through a sorter a group of perfectly and finally sorted cards without altering 40 the order of the other cards. After use the cards contained in that group must be refiled in their original order. In the case where the group consists only of a few cards, the refiled can be done manually without the aid of the sorter. However, if a great number of cards are to be refiled or 45 where the manual work becomes tedious and may lead to errors, even if written indications appear on the card, it will be necessary to put through all the cards to file them together with those which had remained in order, so that all will 50 find their respective consecutive order. Several sortings are thus necessary and either a device is used to automatically insert the cards to refile them in their proper places, or to aid materially 55 in the manual refiled. The description of such device follows:

When the cards of a certain group are sorted (sorting on one or several columns) other cards easily distinguished by different colors, or pref- 60 erably by their thickness or their sizes are inserted therein. The more simple method of identification would be to use ordinary cards but without providing them with asymmetric notches. These cards will be called "separation cards".

Let us suppose, for example, that the various compartments are disposed in such a way that No. XVI (Figs. 1 and 28) which corresponds to the "reject" compartment at the extreme end of the sorter. At a suitable distance of this compartment, XVI, a card distributor 150 is placed and is actuated by a shaft 151. This shaft receives its movement from the main shaft, by means of a pinion or of a chain. It is therefore necessary that each time a card drops into a compartment 75

other than compartment XVI (reject) a separation card be taken into the distributor 150, to replace the card that has dropped. Certain devices actuate the card holder 150 (Fig. 28) for that purpose. A diagram of this device is shown in Fig. 28 and on a larger scale in Fig. 29. The see-saw movement driving the carriage is produced by a crank button 152, carried by a plate held on the main shaft of the sorter and penetrating in the vertical slot 153 of the connecting rod 154. The latter, suitably guided horizontally, normally interlocks with the lug 155 which is a part of the carriage card holder by means of the tilter 156 articulated at 157. This tilter can assume two extreme positions, limited by the stops such as 158 and 159 against which it is maintained by the spring 160, which is tied at 161 on the connecting rod 154 and which is situated on the vertical line of the pivot 157 and above it. Finally, two stops one 162 movable as will be explained, the other 163 fixed on the frame have for their object the tilting of the part 156.

It has been seen that for a card to be sorted it was necessary that the electro-magnet 138 (Fig. 24) be fed with current. A derivation of this current will be used to obtain the desired displacement of the stop 162. To this end, the stop 162 is provided on the lever 164, and is urged by the spring 168 to turn around the pivot 165 fixed to the frame; this lever ends in 166 by a ratchet-motion held by the spring 167 and forming the armature of electro-magnet 169; in the position of ratchet-motion, the tilter 156 bumps against the lug 162; in the contrary case, the tilter passes freely above the lug. Then if the electro-magnet 169 does not receive any current, the tilter 156 bumps against the lug, freeing the part 155 and the carriage will not be driven any more by the connecting rod 154, during its return movement.

During this movement, the embossing 170, acting on the lever 164 latches it with the spring 161, then the tilter 156 bumping against the button 163, takes back the hooking position of the bolt 155. This hooking can be done, (if the electro-magnet 169 receives current) because the parts 155 and 156 are beveled; at the time of their hooking, the spring 160 acts, but not sufficiently for the tilting of the tilter 156.

The button crank 152 must be fixed and the distance between the compartment XVI and the distributor 150 must be determined in such a way that when the electro-magnet 169 receives its current at a definite moment, the separation card arrives in the compartment XVI at the same moment when the selected card would have arrived.

A slight modification of the preceding device will permit the automatic substitution of certain cards for others. Let us suppose that the cards to be taken out of the file have the same punches or holes in certain columns as the cards which are to replace in the file the cards taken out. For instance, in the case of a card upon which all available columns have been used and it is necessary to replace said card by another one, bearing the same identification numbers as the first one. Let us take, first the sort on one column. To that end, a system of reading combs 171 (Fig. 28) is added to the distributor 150. The mounting must be such that, as long as the sorting parameter, i. e., the cipher inserted in the sorting column, of the card being read under the auxiliary combs 171, the electro-magnets 138 and 169 receive no current, but receive current when the two parameters coincide.

To that end, it will suffice, to replace the hand circuit closers in the usual mounting of the electro-magnets mentioned above, by those that are borne by the needles 171 (Fig. 25). The assembly will be as shown in Fig. 30. Let us call 5 the needles of the normal comb 2: A, B, C, D, and those of the comb 171: A', B', C', D'. The current coming from the source arrives in 172 to the central brush of needle A; the exterior brushes of A are united to those of A'. The same applies to B and B', C and C', D and D'. Furthermore, the central brushes of B and A' are connected together as well as C and B', and D and C'. Finally, the central brush 173 of D' is connected with the exterior circuit, that is, with the 10 electro-magnets 169 and 138. Clearly, in order that the current pass through the electro-magnets 169 and 138, the positions of the needles A', B', C', D', must be identical to the positions of A, B, C, D, and the current will not be able to 15 pass.

Under these conditions, when the card to be sorted and the one which awaits sorting under the combs 171 are identical as far as the columns of sorting are concerned, the first card drops 20 into a compartment other than the reject compartment and the second card goes into the latter compartment.

Generally, when several columns are sorted simultaneously it will be necessary to have as 30 many comparing combs as there are columns to sort. The exit brush, such as 173 of the first series is connected with the entry brush (rod 172) of the second series, etc.

It will be often advantageous that all the cards 35 taken out need not be sorted (the sorting without interest in the preceding case, for example, since the parameter of sorting is predetermined), but assembled into the same compartment. This operation can be effected by joining the rods 11, 40 12, 13, 14, which will free the catches 33, 34, 35, 36 and the parts 24 to 27.

It remains now to consider the refiling of the cards taken out. If they are few, the simplest method will be the hand filing which will be 45 easily done due to the indication of the separation cards. When the cards are numerous, let us first assume that separation cards have been inserted, the frame will have in a fixed position a needle 174 (Fig. 31) resting on the upper edge 50 of the cards at a point outside the punching area of the cards. At this particular point, the separation cards will be punched, the grid plate 7 will have a projection 175, so that, it will be lowered by the needle 174 when a separation 55 card passes, and only in that case. Furthermore, in 176, 176', a double brush acts as an interrupter. The latter is normally closed when the needle 174 is in its upper position, but opens when this needle rises, an insulated ring 177, coming between the springs 176, 176', which form the double brush. This interrupter is connected with the circuit of the electro-magnet 169. If the cards to be refiled have been placed in the reserve of the distributor 150, each time that a separation 65 card will pass under the comb 2 this card will fall in the compartment VIII corresponding to the displacement of the only part 24 of Fig. 4, while a card to be refiled, will replace it in the compartment "reject".

What I claim is:

1. A machine for sorting punched cards, which comprises in combination, a plurality of bins for said cards, means for conveying said cards one by one toward said bins, a plurality of movable 75

- blades lying across the path of travel of said cards, said blades being so connected with said bins respectively that the lifting of one blade causes the next card moving toward said blade to fall 5 into the corresponding bin, said blades being piled upon one another and the pile thus formed being provided with a plurality of parallel elongated holes the bottoms of which are stepped in the longitudinal direction of said holes each step 10 corresponding to one blade, the maximum depth of one hole being smaller than the minimum depth of the adjacent hole by a difference equal to the thickness of a blade, a support movable in a horizontal direction parallelly to said holes, a plurality of elements vertically slidable in said support disposed in a line transverse to each of said holes, means for controlling the position of said support with respect to said blades, a vertically 15 slid able element movable in a horizontal direction at right angles to the direction of displacement of said support, means for controlling the position of said element in the last mentioned direction, reading means operative by the perforations in said cards for controlling both the 20 last mentioned means and the displacements of said support, and means operatively interconnected with the means for conveying the cards for moving said element in the vertical direction.
2. A machine for sorting punched cards, which 25 comprises in combination, a plurality of bins for said cards, means for conveying said cards one by one toward said bins, a plurality of movable blades moving across the path of travel of said cards, said blades being so connected with said bins respectively that the lifting of one blade causes the next card moving toward said blade to fall into the corresponding bin, vertically movable means adapted to occupy any of a plurality of positions in a horizontal plane for lifting said blades 30 respectively, means including a plurality of superposed organs slid able horizontally with respect to one another, elastic means for urging all of said organs in the same direction, catches for maintaining said organs in determined relative positions, and fingers for releasing said catches, for controlling the position of the vertically movable means, a plurality of needles located across the path of travel of said cards, means for urging said needles toward said cards, rods, operative by said 35 needles when the latter are positioned opposite respective perforations of the cards, for acting on said fingers, said blades being so shaped and so disposed with respect to one another and to said vertically movable means that for each different position of said vertically movable means in a horizontal plane a different blade is adapted to be lifted by said vertically movable means, and means, operatively interconnected with the means for conveying the cards, for moving said vertically 40 movable means in the vertical direction.
3. A machine for sorting punched cards, which 45 comprises in combination, a plurality of bins for said cards, means for conveying said cards one by one toward said bins, a plurality of movable blades adapted to be brought across the path of travel of said cards, said blades being so connected with said bins respectively that the lifting of one blade causes the next card moving toward said blade to fall into the corresponding bin, vertically movable means, adapted to occupy any of a plurality of positions in a horizontal plane, for lifting said blades respectively, means, including a plurality of superposed organs slid able horizontally with respect to one another, elastic 50 means for urging all of said organs in the same

direction, catches for maintaining said organs in determined relative positions, and fingers for releasing said catches, for controlling the position of said vertically movable means, a source of electric current, a distributor including a plurality of contacts and a brush adapted to move along said contacts, means, operatively interconnected with the means for conveying said cards, for moving said brush along said contacts, a plurality of relays connected with said contacts respectively, a circuit connecting said relays in parallel to said source of current, a brush in said circuit adapted to co-act with said cards so as to close or open said circuit according as there is or there is not a perforation in the card passing in contact with said brush, means controlled by said relays for actuating said fingers respectively, said blades being so shaped and so disposed with respect to one another and to said vertically movable means that for each different position of said vertically movable means in a horizontal plane a different blade is adapted to be lifted by said vertically movable means, and means, operatively interconnected with the means for conveying the cards, for moving said vertically movable means in the vertical direction.

4. A machine for sorting punched cards, which 55 comprises in combination a plurality of compartments for said cards, means for conveying said cards one by one toward said compartments, a plurality of movable blades along the path of travel of said cards, said blades being so connected with said compartments respectively, that the bringing of one blade across said path of travel causes the next card moving toward said blade to drop into the corresponding compartment, a stationary support, a series of organs, slidably supported by one another in directions parallel to a given plane, mounted on said support, a movable member integral with the last organ of said series 60 of organs, means operative by the perforations in said cards for fixing the relative positions of said slid able organs with respect to one another respectively, whereby said member can be brought opposite any of these blades, said member being movable, with respect to said last organ of the series in a direction transverse to said plane so as to be able to bring the blade opposite which it is located across the path of travel of the cards, means operatively interconnected with the means 65 for conveying the cards for moving said member with respect to said last organ of the series, two adjacent successive organs of the series being so connected that they can occupy only two different positions with respect to each other, the values of the distances between these two positions for the successive groups of two adjacent organs of the series forming a geometric progression.

5. A machine for sorting punched cards, which 70 comprises in combination, a plurality of compartments for said cards, means for conveying said cards one by one toward said compartments, a plurality of movable blades along the path of travel of said cards, said blades being so connected with said compartments respectively, that the lifting of one blade across said path of travel, causes the next card moving toward said blade to drop in the corresponding compartment, a stationary support, a series of organs, slidably supported by one another in horizontal directions, mounted on said support, a vertically movable member supported by the last organ of this series, means operative by the perforations in said cards for fixing the relative positions of said slid able organs with respect to one another re- 75

spectively, whereby said member can be brought under any of these blades, and means, operatively interconnected with the means for conveying the cards, for moving said member vertically with respect to said last member of the series, two adjacent successive organs of the series being so connected together that they can occupy only

two different positions with respect to each other, the values of the distances between these two positions for the successive groups of two adjacent organs of the series forming a geometric progression. 5

MARCEL JACOB.
